G. S. SAMUELSON.

STRETCHER.

APPLICATION FILED SEPT. 17, 1918.

1,320,799.

Patented Nov. 4, 1919.

UNITED STATES PATENT OFFICE.

GERALD S. SAMUELSON, OF LONDON, ENGLAND.

STRETCHER.

1,320,799.

Specification of Letters Patent.

Patented Nov. 4, 1919.

Application filed September 17, 1918. Serial No. 254,494.

To all whom it may concern:

Be it known that I, GERALD S. SAMUELSON, major R. A. M. C., a subject of the King of Great Britain, residing aboard H. M. H. S. *Goorkha*, (address general post-office, London, England,) have invented a certain new and useful Improvement in Stretchers, of which the following is a full, clear, and exact description, such as will enable others skilled in the art to which it applies to make and use the same.

This invention relates to canvas stretcher.

One object of the invention is to provide a stretcher that can be used for carrying patients in a recumbent position up or down stairs, through narrow passageways and trenches and around sharp corners.

Another object is to provide a stretcher that can be used for raising or lowering a patient in a shaft or from a vessel's deck to a life boat and which is equipped with a means that tends to protect the patient against the weather.

Another object is to provide a stretcher of the character above described, which is so constructed that it is not necessary to repeatedly lift the patient onto or off of the stretcher when the patient is being transferred to an operating table, bed or other support, or when the patient is being transferred from one railway car to another, or from a car to a boat.

Another object is to provide a stretcher that can be used as a hammock.

And still another object is to provide a light weight, inexpensive stretcher that can be repaired easily in the field by a person possessing no mechanical skill, and which is composed of a number of detachable parts, any one of which is capable of use with another stretcher of the same design. Other objects and desirable features of my invention will be hereinafter pointed out.

Briefly described, my improved stretcher consists of a bed portion formed of canvas or some other suitable fabric, removable side rails arranged in pockets arranged longitudinally along the side edges of the bed portion, loops or handles at the side edges of the bed portion that are adapted to be used for carrying the stretcher when the side rails are not in operative position, flaps connected to the bed portion in such a manner that they can either be folded over the patient lying on the stretcher so as to form a covering for the patient, or can be used

to suspend the bed portion from an overhead supporting structure, such, for example, as a derrick boom, or a single pole carried on the shoulders of the stretcher bearers, and two transversely-disposed members that can be used with the side rails to hold said side rails spaced apart, or which can be used to form transversely-disposed braces when the stretcher is being used as a hammock.

Figure 1 of the drawings is a perspective view, illustrating my improved stretcher suspended from an overhead supporting structure.

Fig. 2 is a transverse sectional view of my stretcher.

Fig. 3 is a perspective view of the stretcher, showing the side rails removed and the flaps folded over the patient.

Fig. 4 is a perspective view, illustrating the stretcher used as a hammock; and

Fig. 5 is a perspective view, illustrating the bed portion suspended by means of the flaps from a single pole that is adapted to be carried on the shoulders of two stretcher bearers.

Referring to the drawings which illustrate the preferred form of my invention, A designates the bed portion of the stretcher which is preferably formed of canvas or some other suitable kind of fabric, B designates two side rails that are removably mounted in pockets C which extend longitudinally of the stretcher along the side edges of the bed portion A, D designates flaps formed of the same kind of material as the bed portion and secured to the side edges of same, E designates loops or hand grips connected to the side edges of the bed portion, and F designates transversely-disposed members formed of metal or some other suitable rigid material and adapted to be combined with the side rails B, as shown in Fig. 1, so as to hold said side rails spaced apart or used in connection with ropes G to form hammock braces, as shown in Fig. 4, when the stretcher is being used as a hammock.

In the preferred form of my invention, as shown herein, the bed portion A is divided longitudinally at the center of the same and the two parts are detachably connected together by a flat retaining strip 1 that extends longitudinally of the stretcher through coöoperating staggered pockets or casings 2 on the meeting edges of the two parts of the bed portion, as shown in Fig. 1. By con-

structing the bed portion in this manner it is possible to transfer a patient from the stretcher onto an operating table, bed or other support without bodily lifting the patient off of the stretcher, for after the bed portion A with the patient thereon has been deposited on the support to which the patient is to be transferred, it is only necessary to remove the retaining strip 1 and then withdraw the two parts of the bed portion from under the patient. It is not essential, however, that the bed portion A be formed in this manner, for if desired, the bed portion could be formed in one piece. The bed portion and flaps can either be formed in one piece and the pockets or casings C formed by separate pieces that are stitched to the side edges of the bed portion, or the flaps can be formed from separate pieces of material that are stitched to the side edges of the bed portion or to pockets or casings that extend longitudinally along the side edges of the bed portion.

The side rails B preferably consist of wooden poles that are adapted to be slipped endwise into and out of the pockets C at the side edges of the bed portion, the intermediate portions of said poles which are arranged in the pockets C being of non-circular shape in cross section, as shown in Fig. 2, and the end portions of said poles being so shaped that they can be grasped conveniently by the hands of the stretcher bearers. The transversely-disposed brace members F are preferably formed from flat strips of metal, and are provided with supporting legs 3 and also non-circular-shaped sleeves 4 through which the side rails B can be inserted, thus producing a rigid frame of rectangular shape in outline whose members can be easily assembled or disassembled. In case it is desired to use the stretcher as a hammock, the side rails B are removed and the members F are arranged between and connected to ropes G that are secured to the bed portion A at the opposite ends of same, as shown in Fig. 4.

The flaps D can either be used to form a covering for the patient, as shown in Fig. 3, or they can be used to suspend the stretcher from an overhead supporting structure, as shown in Figs. 1 and 5. To this end the flaps D are provided at their upper edges with rings or loops 5 through which a pole H can be inserted, as shown in Fig. 5, or to which snaps or hooks 6 on an overhead supporting structure can be connected as shown in Fig. 1.

Under normal conditions the side rails B and transversely-disposed brace members F are used in connection with the bed portion A so as to form a stretcher that can be carried by two stretcher bearers who grasp the handle portions at the ends of the side rails, the flaps D being folded

downwardly over the patient during the operation of transporting the patient. If it is desired to transfer the patient from the stretcher onto a bed, operating table or other supporting structure, this can be easily effected by simply removing the retaining strip 1 and withdrawing the two parts of the bed portion A from under the patient, as previously described. If it is desired to leave the patient on the stretcher the stretcher bearers slip the transverse members F off of the side rails and then withdraw the side rails from the pockets C after the bed portion with the patient thereon has been deposited on the bed or other supporting structure. Notwithstanding the fact that the side rails of the stretcher have been removed, the patient is in condition to be transported quickly, owing to the fact that the hand grips E at the side edges of the bed portion can be used to carry the stretcher.

If the patient is to be carried through a tortuous passageway the side rails are removed and the stretcher carried by the hand grips E, so as to enable the patient to be carried around sharp corners. In carrying the patient through a trench or passageway too narrow for an ordinary stretcher, a single pole H can be slipped through the rings on the flaps D of the stretcher and the poles carried on the shoulders of the stretcher bearers, as shown in Fig. 5. When the patient is to be raised or lowered in a shaft or removed from a vessel's deck to a life boat, the flaps D of the stretcher are connected to a sling carried by the boom of a derrick, as shown in Fig. 1, thus effecting the transfer of the patient without removing the patient from the stretcher.

Having thus described my invention, what I claim and desire to secure by Letters Patent is:

1. A stretcher, comprising a fabric bed portion, two flaps permanently connected to the longitudinal side edges of said bed portion and of such width that they can be lapped one over the other to form a covering for the patient on the stretcher, and means on the free edges of said flaps for connecting them to an overhead supporting structure, thereby enabling said flaps to be used either as a covering for the patient or to suspend the bed portion from a supporting structure.

2. A stretcher, comprising a fabric bed portion provided at its longitudinal side edges with pockets, rigid side rails removably mounted in said pockets, transversely-disposed brace members detachably connected to said side rails, fabric flaps permanently connected to the longitudinal side edges of the bed portion and being of such width that they can be lapped one over the other to form a covering for the patient on

the stretcher, and means on the free edges of the flaps for securing the flaps to an overhead supporting structure.

3. A stretcher, comprising a frame composed of two rigid side rails and two transversely-disposed brace members, each of said brace members comprising a rigid part provided at its opposite ends with non-

circular shaped sleeves for receiving the side rails and integral legs that depend from said sleeves, and a fabric bed portion provided with longitudinally-extending pockets through which the side rails of said frame pass.

GERALD S. SAMUELSON
